Primary Examiner — Robert M. Spear(74) *Attorney, Agent, or Firm* — Fay Sharpe LLP(57) **CLAIM**

The ornamental design for a tire tread, as shown and described.

DESCRIPTION

FIG. 1 is a perspective view of a tire tread of the present application;

FIG. 2 is a front view thereof;

FIG. 3 is a side view thereof;

FIG. 4 is an enlarged partial perspective view thereof; and, FIG. 5 is an enlarged partial front view thereof.

The broken lines and the region defining the inner bead and that portion of the sidewall between the broken lines form no part of the claimed tire tread design, and are included for the purpose of illustrating the full tire. The tread pattern is understood to uniformly repeat throughout the circumference of the tire. The other side view of the tire is identical to the illustrated side view.
